SPARK PLUG

Henry K. King, Bethesda, Md.

Application November 27, 1941, Serial No. 420,625

19 Claims. (Cl. 123—169)

(Granted under the act of March 3, 1883, as
amended April 30, 1928; 370 O. G. 757)

My invention relates in general to spark plugs and has particular reference to spark plugs utilizing a series of spark gaps as distinguished from the more conventional plug having only a single gap.

It has long been common practice to manufacture different types of plugs for different fields of application. These can be divided in general into two classes. Engines which operate at relatively low temperatures require a "hot" plug, i. e., a plug designed to operate at a high temperature to prevent oil deposit thereon which otherwise would tend to cause the plug to misfire, commonly referred to as "fouling." On the other hand, engines which operate at relatively high temperatures require a "cold" plug, i. e., a plug designed to operate at a low temperature to prevent preignition which otherwise would tend to cause the plug to fire ahead of time.

In modern high powered combustion engines, such as for example those used on aircraft, it has long been a problem to design a spark plug which will give satisfactory performance throughout extremes in operating temperature conditions of the engine. When the engine is operating at full power, its temperature is of course at a maximum and hence there is a tendency towards preignition of the plug, but when the engine is operating at minimum power its temperature is obviously also at a minimum and thus there is a tendency towards fouling.

It is therefore a broad object of my invention to provide an improved spark plug for a combustion engine which will maintain a substantially uniform temperature and thereby render satisfactory service throughout extremes in operating temperatures of the engine.

A specific object of my invention is to provide a spark plug having gaps in series in which the base member forming the outer electrode is spaced from the outermost intermediate electrode to form a chamber therebetween to permit entry therein of the hot gases of combustion which tends to maintain the exposed surface of the intermediate electrode at a constant temperature to thereby prevent fouling.

Another object is to provide a spark plug utilizing gaps in series in which the intermediate electrodes are so arranged as to provide a heat path of high conductivity whereby the extreme heat generated therein when the engine is operating at high temperature may be dissipated quickly to prevent preignition.

These and other objects of my invention will become more apparent from the following de-

tailed description and from the attached drawing.

With respect to the drawing in which like reference numerals indicate like parts:

5 Fig. 1 is a vertical section of a spark plug illustrating a preferred embodiment of my invention, and

Fig. 2 is a bottom plan view of the plug shown in Fig. 1.

10 With reference now in particular to Fig. 1, my improved spark plug contains an inner or central metallic electrode 1 which is tapered slightly and cylindrical in contour. The upper portion of electrode 1 is made hollow so that this section will have a relatively low heat conducting capacity. This feature of construction prevents overheating of the top of the plug which otherwise might cause damage to the high voltage lead (not illustrated) which is attached to the top of electrode 1 in any well known manner.

15 Surrounding electrode 1 are a plurality of sleeves 3 and 5 made of any good conductive metal which form intermediate electrodes. These sleeves are also tapered to the contour of the central electrode and are electrically separated from each other and from the central electrode by means of tapered sleeves 2 and 4 which may be made from any suitable non-conductor such as, for example, sheet mica, and preformed to size if desired.

20 Insulating sleeves 2 and 4 may extend for substantially the entire length of the central electrode 1 to increase the gas sealing qualities of the plug. Intermediate sleeve electrodes 3 and 5 terminate, however, at substantially the juncture between the hollow and solid portions of the central electrode. To fill the space above these intermediate electrodes, insulating sleeves 7 and 8, 25 also tapered and preformed if desired, are positioned between insulating sleeves 2 and 4, and 30 4 and 6 respectively.

25 An annular metallic member 9 having a frustoconical shouldered portion 10 is provided for holding the alternately arranged electrode sleeves and insulating sleeves firmly in position with respect to the central electrode. Being tapered, the sleeves will of course be tightened further upon heating.

30 A shell 11 is provided for receiving the electrodes and contains an upper female threaded cylindrical portion 12 for receiving a cylindrical shielding member 13. A lower male threaded base portion 14 provides for screw insertion of the plug through an engine block 15 into a combustion chamber of the latter. Shell 11 is

also provided with a horizontal shoulder 16 between which and the wall 15 is inserted the usual gasket member 17 and may also include the usual polygonal shaped surface 18 for receiving a wrench.

The inner surface of shield member 13 may be lined with an insulating sleeve 19, and insulating washers 20 may be disposed horizontally between sleeve 19 and insulating sleeve 6.

To assist in fixing the electrode and insulating sleeves in their positions, a cap member 21 may be secured in place between the top of the sleeves and an outwardly flared portion formed on the central electrode 1.

The lower cylindrical screw portion 14 of shell 11 receives the assembly of electrode and insulating sleeves and is spaced from the outer surface of electrode sleeve 5 by the particular construction of member 9 and insulating sleeve 6 to form a gas chamber 22 therebetween. The bottom of portion 14 is turned inwardly at 23 as shown to form a gas nozzle 24 whereby the gases of combustion which enter the chamber upon the "compression" stroke of the engine may be subsequently drawn outwardly from the chamber with a high velocity to render the gap self-cleaning.

The hot gases circulating in chamber 22 also maintain the outer surface of electrode 5 at an elevated temperature which is sufficient to prevent "fouling" between this electrode and the inner wall of the lower portion 14 of shell 11.

It will be noted that the intermediate sleeve electrodes 3 and 5 terminate at substantially the juncture between the hollow and solid portions of electrode 1, which juncture is formed substantially at the top of member 9. By providing a construction of this type, that portion of the plug above the intermediate electrodes 3 and 5 will have a relatively low heat conductivity with the result that the greater part of the heat in the plug which will rise rapidly from the spark area because of the highly conductive heat path provided by the metallic electrodes 3 and 5 and solid electrode 1 will be driven outwardly therefrom in substantially a transverse direction across a relatively high conductive heat path comprising member 9, shell 11 and gasket 17 to the engine block 15. This rapid dissipation of heat generated is effective to prevent local overheating of the electrodes in the area adjacent the spark path and will thereby prevent preignition under high temperature operating conditions.

The operation of my improved plug is as follows: High voltage is supplied in any well known manner as from a spark coil, one side of which is grounded, through a suitably insulated conductor to the top of the central electrode 1. Since one side of the spark coil is grounded, as is also the engine block 15, an arc will be formed between the central electrode 1 and electrode 3 from whence it will jump to electrode 5 and then to base portion 14.

Recapitulating, it will be evident that the structure which has been described is a distinctive and meritorious advance in the art in that it provides a spark plug which will render satisfactory operation over extreme differentials in operating temperatures. When the temperature is comparatively low, the plug will not foul between the outer electrode and intermediate electrode, particularly at the upper part of the chamber 22, where fouling is most likely to occur; the gas action into and out of chamber 22 across nozzle 24 renders the plug self-cleaning; and the

highly conductive heat path furnished by the central and intermediate electrode assembly serves to prevent local overheating of the electrodes in the area adjacent the spark gap when the operating temperature is high to thereby minimize possibilities for preignition.

In conclusion, it will be evident to those skilled in the art that various changes may be made in the form, details of construction and arrangement of parts herein described without departing from the spirit and scope of my invention. I therefore desire it to be understood that only such limitations as are imposed by the prior art shall be placed upon the appended claims.

The invention described herein may be manufactured and used by or for the Government of the United States of America for governmental purposes without the payment of any royalties thereon or therefor.

Having now fully described my invention, what I claim is:

1. In a spark plug utilizing spark discharge between a plurality of gaps in series, the combination comprising an inner electrode, at least one sleeve of conductive material constituting an intermediate electrode, the bottom edge of said conductive sleeve forming an annulus coplanar with the bottom edge of said inner electrode, means for insulating said inner and intermediate electrodes from each other, and a hollow base portion forming an outer electrode, the inner wall of said base portion being spaced from the exterior surface of the outermost intermediate electrode to form a chamber therebetween.

2. The combination of claim 1 wherein the chamber has a reduced cross-sectional area at the spark path between the intermediate electrode and the outer electrode to form a gas nozzle.

3. In a spark plug utilizing spark discharge between a plurality of gaps in series, the combination comprising an inner electrode, at least one annular sleeve of conductive material arranged coaxially therewith and forming an intermediate electrode, an annular sleeve of non-conductive material for insulating said inner and intermediate electrodes from each other, and a tubular male threaded base portion disposed coaxially with said electrodes forming the outer electrode, the inner wall of said base portion being spaced from the exterior surface of the outermost intermediate electrode to form a gas chamber therebetween for rendering the spark gap self-cleaning, said chamber having a relatively small area adjacent the spark path and a substantially greater area thereabove.

4. In a spark plug utilizing spark discharge between a plurality of gaps in series, the combination comprising an inner electrode, a plurality of annular sleeves of conductive material forming intermediate electrodes, sleeves of non-conductive material for insulating the inner electrode from the intermediate electrode nearest thereto and for insulating the intermediate electrodes from each other and a tubular base member forming the outer electrode, said base surrounding said inner and intermediate electrode assembly and being spaced therefrom to form a gas chamber between the inner wall of said base and the exterior surface of the outermost intermediate electrode.

5. The combination of claim 4 characterized by the fact that the cross-sectional area of the chamber at the spark path between the outermost

intermediate electrode and the outer electrode is reduced to form a gas nozzle.

6. In a spark plug utilizing spark discharge between a plurality of gaps, the combination comprising a tapered inner electrode, a plurality of tapered conductive sleeves disposed coaxially with said inner electrode and forming intermediate electrodes, said intermediate electrodes being arranged to provide a spark path thereacross normal to the longitudinal axis of said inner electrode, insulating means for electrically separating the inner electrode from the intermediate electrode nearest thereto and for electrically separating the intermediate electrodes from each other, and a tube like body member forming the outer electrode, said body member being disposed coaxially with said inner and intermediate electrodes and spaced therefrom to form a gas chamber between the inner wall of said body member and the exterior surface of the outermost intermediate electrode.

7. The combination of claim 6 wherein the cross-sectional area of the gas chamber at the spark path between the intermediate and outer electrode is reduced to form a gas nozzle.

8. In a spark plug utilizing spark discharge between a plurality of gaps, the combination comprising a tapered central electrode, a plurality of annular conductive sleeves of frusto-conical contour disposed co-axially with said central electrode and forming intermediate electrodes, sleeves of insulating material for separating the central electrode from the intermediate electrode nearest thereto and the intermediate electrodes from each other, and a tubular base member forming the outer electrode, said base member being disposed coaxially with said central and intermediate electrodes and spaced therefrom to form the side walls of a gas chamber between the inner wall of said base member and the exterior surface of the outermost intermediate electrode, the inner diameter of said base member adjacent the spark path being such as to form a nozzle for gas entry into said chamber.

9. In a spark plug, the combination comprising a tubular base member for insertion into a gas explosion chamber and serving as an outer electrode, a central electrode, at least one sleeve of conductive material forming an intermediate electrode, said central and intermediate electrodes projecting downwardly into said base member and terminating co-planar adjacent the bottom of said base member to form series spark gaps thereacross, insulating means for electrically separating the central from the intermediate electrodes, and a gas chamber formed by the inner surface of said base member and the outer surface of the outermost intermediate electrode.

10. In a spark plug, the combination comprising a tubular male threaded base member for screw-insertion into a gas explosion chamber and serving as an outer electrode, an inner electrode, at least one sleeve of conductive material forming an intermediate electrode, means for insulating said intermediate electrode from said inner electrode, said inner and intermediate electrodes being tapered and having their bases of larger diameter projecting downwardly into said base member and terminating co-planar with the bottom edge of said base member to form series spark gaps thereacross and a gas chamber formed by the inner surface of said base member and the outer surface of the outermost intermediate electrode, the inner diameter of said base member adjacent the spark path being restricted

to form a nozzle for gas entry into said chamber.

11. In a spark plug, the combination comprising a tubular male threaded base member for screw insertion into a gas chamber and serving as an outer electrode, a tapered central electrode, intermediate electrodes comprising tapered sleeves of conductive material surrounding said central electrode and electrically separated therefrom and from each other by tapered sleeves of insulating material, the bases of larger diameter of said central and intermediate electrodes projecting downwardly into said base member and terminating co-planar with the bottom thereof to form series spark gaps between central and outer electrodes, and an annular gas chamber the sides of which are formed by the inner surface of said base member and the outer surface of the outermost intermediate electrode, the inner diameter of said base member adjacent the spark path being restricted to form a nozzle for gas entry into said chamber.

12. In a spark plug utilizing a spark discharge between a plurality of gaps in series, the combination comprising a central electrode, said electrode having a lower solid portion and an upper hollow portion, at least one sleeve of conductive material forming an intermediate electrode, said intermediate electrode being terminated at substantially the juncture of the solid and hollow portions of said inner electrode, a base portion forming the outer electrode and means for insulating said electrodes relative to each other.

13. In a spark plug utilizing a spark discharge between a plurality of gaps in series, the combination comprising a central electrode, said electrode having lower solid and upper hollow portions, at least one sleeve of conductive material arranged coaxially with said central electrode to form an intermediate electrode, said conductive sleeve being terminated at substantially the juncture between the solid and hollow portions of said central electrode, an insulating sleeve disposed between said electrodes and a base portion forming the outer electrode into which the lower portions of said central and intermediate electrodes are projected to form a series of gaps therebetween, the inner surface of said base portion being spaced from the exterior surface of the outermost intermediate electrode to form a gas chamber therebetween to render the plug self-cleaning.

14. In a spark plug, the combination comprising a base member for insertion into a gas explosion chamber and serving as an outer electrode, a central electrode having a lower solid portion and an upper hollow portion, at least one intermediate electrode, the top of said intermediate electrode being terminated substantially adjacent the juncture between the solid and hollow portions of said central electrode and the bottom thereof being terminated co-planar with the bottom of said base member to form a series of spark gaps between said central and outer electrodes, means for insulating said central and each of said intermediate electrodes from one another, and separator means including an insulating member for spacing the inner surface of said base member from the exterior surface of said outermost intermediate electrode to form a gas chamber therebetween.

15. The combination of claim 14 characterized by the fact that the cross-sectional area of said chamber at the spark path between said intermediate and outer electrodes is reduced to form a gas nozzle.

16. In a spark plug the combination comprising a base member for insertion into a gas explosion chamber and serving as an outer electrode, a tapered central electrode, said electrode being hollow above the primary path of heat flow away therefrom and solid therebelow, at least one tapered sleeve of conductive material arranged coaxially with said central electrode to form an intermediate electrode, the top end of said sleeve being terminated at substantially the juncture between the solid and hollow portions of said central electrode and the bottom end thereof being terminated co-planar with the bottom end of said base member to form a series of spark gaps, non-conductive means for insulating said central and each of said intermediate electrodes from one another for substantially their entire lengths and separator means including a non-conductive member for spacing the inner surface of said base member from the exterior surface of said outermost intermediate electrode to form a gas chamber therebetween whereby said plug is rendered self-cleaning.

17. The combination of claim 16 characterized by the fact that the transverse sectional area of said chamber at the spark path between said intermediate and outer electrodes is reduced to form a gas nozzle.

18. In a spark plug, the combination comprising

ing a base member for insertion into a gas explosion chamber and serving as an outer electrode, a tapered central electrode, said electrode being hollow above the primary path of heat flow away therefrom and solid therebelow, at least one tapered sleeve of conductive material arranged coaxially with said central electrode to form an intermediate electrode, the top end of said sleeve being terminated at substantially the juncture between the solid and hollow portions of said central electrode and the bottom end thereof being terminated co-planar with the bottom end of said base member to form a series of spark gaps, non-conductive sleeves for insulating said central and each of said intermediate electrodes from one another for substantially their entire lengths and separator means including a non-conductive sleeve for spacing the inner surface of said base member from the exterior surface of said outermost intermediate electrode to form a gas chamber therebetween whereby said plug is rendered self-cleaning.

19. The combination of claim 18 characterized by the fact that the transverse sectional area of said chamber at the spark path between said intermediate and outer electrodes is reduced to form a gas nozzle.

HENRY K. KING.
